UNITED STATES PATENT OFFICE.

EUGENE T. TURNER, OF NEW YORK, N. Y., ASSIGNOR TO AMERICAN PLAYER ACTION COMPANY, A CORPORATION OF WEST VIRGINIA.

ACTUATING MECHANISM OF PIANO-PLAYERS.

1,169,442.

Specification of Letters Patent.

Patented Jan. 25, 1916.

Application filed December 26, 1913. Serial No. 808,823.

To all whom it may concern:

Be it known that I, EUGENE T. TURNER, a citizen of the United States, residing in the city, county, and State of New York, and whose post-office address is No. 2595 5 Third avenue, New York, have invented certain new and useful Improvements in Actuating Mechanism of Piano-Players, of which the following is a specification.

This invention aims to provide certain 10 improvements in piano players and especially in the arrangement and design of the pneumatics and their relation to the action of the piano.

The invention aims to provide a simple 15 mechanism of this sort which works with good power and speed, which is very compact so as to go into a comparatively small case and which is readily accessible for 20 adjustment or repair.

In a prior application, No. 655,076 filed 25 Oct. 16, 1911 I have described a compact arrangement of wind chests with pneumatics arranged vertically at the backs of the chests and having arms projecting at an angle from near the hinged end of the movable member of each pneumatic so as to 30 secure a construction of slight depth from front to back.

The present construction is an improvement thereon in which the pneumatics have 35 their broader upper ends inclined forward, which permits the bringing of the pneumatics closer to the stickers or similar parts of the piano action and which permits the 40 shortening of the arms carried by the movable members of the pneumatics so that the depth of the construction from front to back is even less than in the previous design and so that more power is secured.

Other points of advantage are referred 45 to hereinafter.

The accompanying drawings illustrate embodiments of the invention.

Figure 1 is a vertical sectional view 50 through the wind chests and adjacent parts; Fig. 2 is a similar view of a slightly modified construction.

Referring now to the accompanying drawings, the wind chests A extend entirely across the front of the piano action in front of the vertical stickers B which transmit the upward movements of the rear ends of the keys C to the wippens D which operate 55 the hammers. The several wind chests A are in communication with each other at

their ends and are in communication with the pumper by which a partial vacuum is maintained in said chests. At the backs of the wind chests are located the bellows or 60 pneumatics E, F, those in one row being staggered relatively to those in the next row so as to bring the center of each pneumatic in line with one of the stickers B or equivalent devices for transmitting the 65 movement of the pneumatic to the hammer. For each pneumatic there is a set of valves G and H which open communication from the atmosphere or from the wind chest A respectively to the passage J leading to the 70 pneumatic; each set of valves being controlled by a diaphragm K, the upper side of which is exposed within the wind chest and the lower side of which is exposed to a passage L which communicates through 75 suitable tubing with one of the openings in the tracker board. The passage L also communicates through a bleed hole M with the wind chest. Thus when an opening in the tracker board registers with an opening in 80 the note sheet air is admitted to the passage L, the diaphragm K is moved upward carrying with it the stem N of the valves G and H and shutting off communication with the atmosphere and opening communication of 85 the pneumatic with the wind chest so as to collapse the pneumatic. When the opening in the tracker board is covered there is a gradual restoration of the balance on opposite sides of the diaphragm K, by the passage of air through the bleed hole M and the valves are lowered and the pneumatic 90 expanded to its position of rest.

The pneumatics are arranged in upright 95 positions at the backs of the wind chests so as to economize space in a transverse direction and are provided each with an arm O attached at an angle to the movable member F near the hinge end of the pneumatic, the sticker or equivalent part of the action 100 being operated by the upward movement of said arm either directly or indirectly through intermediate devices hereinafter described. In the foregoing application the pneumatics are mounted with their fixed 105 members in vertical position. Space may be further economized, however, by mounting them in the position illustrated in the present drawings, that is with the end of the member E which is opposite the hinge 110 inclined away from the stickers; so that the free end of the movable member F inclines

to the rear of a vertical line through the hinge when the pneumatic is expanded and to the front of said line when the pneumatic is collapsed (as shown in dotted lines).
 5 This position of the movable member F of the pneumatic permits of the bringing of the action comparatively close to the pneumatics and wind chests and permits the use of comparatively short arms O with a corresponding 10 powerful stroke, these arms being in fact substantially shorter than the length of the movable members F of the bellows, so that the arms move with a shorter and more powerful stroke than that of the members F. The stroke of the pneumatic is, of course, made great enough to produce the desired extent of vertical motion of the arms O and the ports are made large enough to secure a quick stroke. The collapsing 15 stroke of the pneumatics is limited by the striking of a pad P against the end of a screw Q passing through the fixed member E of the pneumatic and accessible from the front to permit adjustment by a long bladed screw driver.
 20

The arm O is preferably adjustable angularly, being pivoted on the block R near the hinged end of the movable member of the pneumatic, through which block passes an adjusting screw S, the end of which bears against a lug T on the arm and the head of which lies between successive wind chests and is accessible from the front by a long bladed screw driver. The arms O 30 of the first and second tiers of pneumatics are connected by links U with the rear portions of levers V pivotally connected to a block or rail W on the underside of the lowermost wind chest, the forward end of 35 each lever V extending under a forward projection X on the corresponding sticker B. It will be understood that each of the stickers B has a projection X, these projections being in line with each other along 40 the entire row of stickers. The lowermost tier of pneumatics has an arm O' attached to the movable member of each of the pneumatics and similar in every respect to the arms O except that it is long enough to 45 extend under the forward projection X of the corresponding sticker. This construction, with one tier of pneumatics having arms O' which act directly upon the stickers and with the other tiers of pneumatics 50 having arms O which act indirectly on the stickers is especially adapted for pianos in which the actions are very short in the vertical dimension. Where, however, the stickers can be made long enough, as in Fig. 2, 55 to extend past three tiers of pneumatics the stickers B' of one set will be operated directly by arms O' of the lowermost pneumatics, the stickers B² of the next set will 60

be operated directly by identical arms O' on the next tier of pneumatics and the 65 stickers B³ of the third set will likewise be operated by arms O' of the highest tier of pneumatics.

Though I have described with great particularity of detail certain specific embodiments of my invention yet it is not to be understood therefrom that the invention is restricted to the particular embodiments disclosed. Various modifications thereof in detail and in the arrangement and combination of the parts may be made by those skilled in the art without departure from the invention.

What I claim is:—

1. In combination a wind chest, pneumatics mounted in upright position on the back of said wind chest and arms attached at approximately or substantially a right angle to the movable members of the pneumatics near the hinged end thereof, the 85 fixed members of the pneumatics having their ends opposite the hinges inclined forwardly so as to permit the shortening of said arms and the bringing of the pneumatics close to the piano action whereby to 90 secure compactness and a powerful stroke.

2. In combination a wind chest and a set of pneumatics mounted at the back of said wind chest in approximately upright positions with the fixed members of the 95 pneumatics projecting forwardly and the movable members positioned to swing to the front and rear of a vertical position as the pneumatics are collapsed and expanded, and arms attached to said movable members 100 near the hinged end thereof and extending therefrom at approximately or substantially a right angle so as to swing above and below a horizontal position as the pneumatics are collapsed and expanded.

3. In combination a wind chest and a set of pneumatics mounted at the back of said wind chest, the movable members of the pneumatics being positioned so as to swing to the front and rear of a vertical 110 position as the pneumatics are collapsed and expanded, and arms attached to said movable members near the hinged end thereof and extending therefrom at approximately or substantially a right angle 115 so as to swing above and below a horizontal position as the pneumatics are collapsed and expanded.

In witness whereof, I have hereunto signed my name in the presence of two 120 subscribing witnesses.

EUGENE T. TURNER.
